UNITED STATES PATENT OFFICE.

CONRAD WERRA, OF WAUKESHA, WISCONSIN.

PISTON CONSTRUCTION.

1,195,305.

Specification of Letters Patent. Patented Aug. 22, 1916.

Application filed June 18, 1914. Serial No. 845,774.

To all whom it may concern:

Be it known that I, CONRAD WERRA, a citizen of the United States, and resident of Waukesha, in the county of Waukesha and

5 State of Wisconsin, have invented new and useful Improvements in Piston Construction, of which the following is a description, reference being had to the accompanying drawings, which are a part of this specification.

10 This invention relates to improvements in piston construction.

In the manufacture of internal combustion engines the tendency is toward high speed engines which are constructed as lightly as possible. In engines of this type the cylinders and pistons are usually formed 15 of iron and as iron is comparatively a heavy metal, considerable power is lost in over- 20 coming the inertia of movement of the heavy piston at the end of each reciprocation. A further objection to pistons formed of iron is that the weight causes unnecessary vibration which increases the wear on the parts 25 and also consumes additional power.

It is one of the objects of the present invention to overcome the before mentioned objectionable features and provide a piston construction which is of less weight than 30 the pistons now in use and in which provision is made for taking the wear of the parts.

A further object of the invention is to provide a piston construction whereby the major portion of the piston may be formed of aluminum or other light weight metal protected with other metal at points subjected 35 to the greatest wear.

40 A further object of the invention is to provide a piston construction in which parts are adapted to conform to the irregularities in shape of the inner wall of the cylinder of the engine of which the piston forms a part.

With the above and other objects in view, 45 the invention consists of the improved piston construction and its parts and combinations as set forth in the claims, and all equivalents thereof.

In the accompanying drawing in which 50 the same reference characters indicate the same parts in all of the views: Figure 1 is a side view of a piston construction embodying the improvements; Fig. 2 is a vertical

central sectional view thereof taken on line 2—2 of Fig. 1; and Fig. 3 is a transverse 55 sectional view thereof taken on line 3—3 of Fig. 1.

Referring to the drawing the numeral 5 indicates the body portion or shell of the piston which is formed of aluminum or 60 other light weight metal, and is provided with the usual inwardly extending bored bosses 6 to receive the cross pin on which the connecting rod is pivotally mounted. The bosses are reinforced by ribs 7 which ex- 65 tend upwardly and connect with the top or end wall 8 of the piston. One of the bosses is provided with a threaded opening 9 to receive a set screw for clamping the connecting rod cross pin in position. This end wall 70 is of convex or crowned form to better resist the strain of the explosion. The piston is cast partly around unbroken bearing rings 10 and 11 preferably of iron which are of slightly larger diameter than the piston in 75 order to engage the surface of the bore of the cylinder and have inner, upper and lower surfaces sufficiently smooth to prevent the body portion of the piston from adhering thereto. The rings 10 are of rectangular 80 form in cross section and fit snugly but radially movably in the grooves 12 formed in casting the piston. The inner upper portion of the bearing ring 11 is also of rectangular form in cross section with a flanged 85 bearing portion 13 extending toward the open end of the piston. This ring also fits snugly and radially movably within a groove 14 formed in casting the piston and also has inner, upper and lower surfaces sufficiently 90 smooth to prevent the body portion of the piston from adhering thereto. The ring 11 is provided with annular grooves 15 to receive split piston packing rings of ordinary 95 construction.

In casting the improved pistons, the rings cut to size and having smooth surfaces, are placed in a die or sand mold and the molten aluminum or other light metal is then poured into the mold and engages the 100 smooth upper, inner and lower surfaces of the bearing rings. As the coefficient of expansion of aluminum is greater than iron the aluminum in cooling in the mold will contract and draw radially away from the 105 inner surfaces of the bearing rings and form

annular spaces 16 which permits the expansion of the piston when doing its work within the cylinder without unduly straining the rings. These annular expansion spaces also 5 serve to permit the rings to move with relation to the piston body and to adapt themselves to the irregularities of the cylinder bore and thus eliminate undue friction and wear. The light weight of the piston due 10 to the major portion being formed of aluminum requires less power to reciprocate it back and forth and vibration is reduced to a minimum.

From the foregoing description it will be 15 seen that the piston construction provides a light weight piston well adapted for the purpose described and which possesses the necessary strength to withstand the wear they are subjected to.

20 What I claim as my invention is:

1. A piston construction, comprising a body portion formed of a light weight metal, and a series of unbroken bearing rings surrounding said body portion and spaced 25 therefrom, said bearing rings being formed of a metal of greater weight than the weight of the metal of the body portion.

2. A piston construction, comprising a plurality of unbroken bearing rings, and a 30 body portion cast within the rings and spaced therefrom, said body portion being formed of a metal of less weight than the weight of the metal of the bearing rings.

3. A piston construction, comprising a 35 body portion formed of a light weight material and provided with a plurality of annular grooves, and unbroken bearing rings surrounding said body portion and extending into said grooves and spaced from said 40 body portion, the outer diameter of the bearing rings being greater than the outer diameter of the body portion.

4. A piston construction, comprising a body portion formed of light weight material and provided with a plurality of annular grooves, and unbroken bearing rings 45 surrounding said body portion and entering the grooves and spaced from said body portion, the outer diameter of the bearing rings 50 being greater than the outer diameter of the body portion, one of said bearing rings provided with an annular packing ring groove.

5. A piston construction, comprising a body portion formed of light weight material and provided with a plurality of annular grooves, and unbroken bearing rings 55 surrounding said body portion and extending into said grooves and spaced from said body portion, the grooved portions being of a diameter to permit greater expansion of 60 the body portion than the bearing rings.

6. A piston construction, comprising a body portion formed of aluminum and having a plurality of peripheral grooves and a 65 crowned end, and unbroken bearing rings

mounted in said grooves and spaced from the outer walls of said grooves and engaging the side walls thereof to permit greater expansion radially of the body portion, one of said bearing rings being provided with an 70 annular packing ring groove.

7. A piston, comprising a body portion, and bearing rings non-removably mounted on said body portion and spaced therefrom, the coefficient of expansion of the body portion being greater than that of the rings and the parts being mounted to permit the expansion of said parts.

8. A piston, comprising a body portion, and bearing rings mounted on said body portion and spaced therefrom, the coefficient of expansion of the body portion being greater than that of the rings and the parts being mounted to permit the expansion of said parts.

9. A piston, comprising a body portion of aluminum, and bearing rings non-removably spaced thereon, one of said bearing rings having an annular groove for receiving a packing ring.

10. A piston, comprising a body portion of aluminum, and unbroken bearing rings non-removably spaced thereon, one of said bearing rings having an annular groove for receiving a packing ring.

11. In a piston construction, the combination with a plurality of cast-iron bearing rings, of a body portion of aluminum non-removably cast within the rings and spaced therefrom, the coefficient of expansion of the body portion being greater than that of the rings and the parts being mounted to permit the expansion.

12. A piston, comprising a body portion having a plurality of annular grooves, and bearing rings non-removably mounted in said grooves, the coefficient of expansion of the body portion being greater than the rings, the inner surfaces of said rings being of greater diameter than the peripheries of the grooved portions to permit the body portion to expand radially to a greater extent than the bearing rings.

13. A piston, comprising a body portion having a plurality of annular grooves, and bearing rings non-removably mounted in said grooves, one of said rings provided with an annular groove for receiving a packing ring, the coefficient of expansion of the body portion being greater than the bearing rings, the inner surfaces of said bearing rings being of greater diameter than the peripheries of the grooved portions to permit the body portion to expand radially to a greater extent than the bearing rings.

14. A piston, comprising an aluminum body portion having a plurality of annular grooves, and iron bearing rings non-removably mounted in said rings, one of said rings provided with an annular groove for receiv-

ing a packing ring, the inner surfaces of said bearing rings being of greater diameter than the peripheries of the grooved portions of the piston body to permit the body portion to expand radially to a greater extent than the bearing rings.

In testimony whereof, I affix my signature, in presence of two witnesses.

CONRAD WERRA.
